BEVEL

Charles Psholka, Agawam, Mass.

Application March 19, 1956, Serial No. 572,513

1 Claim. (Cl. 33—102)

This invention relates to new and useful improvements in tools and is directed more particularly to improvements in bevels as used by toolmakers, machinists and the like.

The principal objects of the invention are directed to the provision of a bevel for toolmakers, machinists and the like which is constructed and arranged for precision work and not only is readily and easily adjusted but also maintains adjustment in such a manner as to avoid accidental misadjustment.

According to novel features of the invention, the bevel is adapted for adjustment to a very fine degree and the blade is secured in adjusted position by a means which does not tend to disturb the adjustment, all to the end that the tool is suited for work requiring the utmost precision.

Another object is to provide a strong and durable apparatus of the above mentioned type, with parts thereof constructed and coacting so as to reduce costly machining operations and facilitate manufacture as by molding or die casting and also to facilitate and expedite assembly thereto of various coacting parts.

Another object is in general to provide an improved structure of the above mentioned type that will be well adapted to meet varying requirements and also the conditions of hard practical use.

Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claim.

In the accompanying drawings in which is shown a preferred embodiment of the invention and in which similar reference characters refer to similar parts throughout the several views;

Fig. 1 is a plan view of a bevel embodying the novel features of the invention;

Fig. 2 is a sectional elevational view on the line 2—2 of Fig. 1;

Figs. 3 and 4 are side and front elevational views respectively of the pivot member of the bevel shown in Figs. 1 and 2;

Fig. 5 is an inverted plan view of one end of the body of the bevel; and

Fig. 6 is an inverted plan view of the cover plate of the bevel.

Referring now to the drawings more in detail, the novel features of the invention will be described.

An elongated body or support 2 is provided which, at its forward or pivot end, is provided with a bore or opening 4 for a pivot member to be described.

A recess 6 is formed around the opening 4. The opposite end of the body 2 is provided with an opening 8 for a lock and an elongated groove 10 extends between the recess 6 and opening 8, for a lock bar.

2

A pivot member 12 is circular in form and has an annular flange 14. The said member 12 is rotatable in the bore 4 and recess of the body 2 and a cover plate 16 is secured to the lower face of the body 2 by suitable means such as screws 18. Holes 20 are provided in the plate 16 for the screws 18 which threadedly engage the body. The member 12 is held in the body for rotation relative thereto by means of the plate 16 which is provided with an opening 16'.

10 The pivot member is formed to have a slot 24 disposed horizontally and a vertically disposed opening 26 for a nut as will appear. The pivot member 12 is also provided with a horizontal hole 28 extending into the vertical opening 26 thereof.

15 A blade 30 is slidable in the slot 24 of the pivot member and is provided with a longitudinal groove 32 in the lower face thereof.

A hook member 34 is inserted in the opening 28 and has an inner threaded end 36 and an outer hook end 38. 20 A nut 40 disposed in the vertical opening 26 is in engagement with the threaded end 36 of the hook member which engages in the groove of the blade, as shown.

By tightening the nut 40, the hook end 38 of member 34 in the groove of the blade draws the blade inwardly of 25 the slot 24 of the pivot member to clamp said blade in the desired position of longitudinal adjustment.

As stated, the pivot member is rotatable in the body for adjusting the angularity of the blade. Means is provided for locking the member 12 in positions of angular adjustment.

30 To that end, a stud 44 has a lower end 46 fixed in the plate 16 in a suitable manner, as by a press fit. The upper end of the stud is threaded and said stud is enlarged intermediate its ends, as shown.

35 A lock nut 48 is in threaded engagement with the upper end of the stud 44 and has a more or less conical or chamfered lower end 48'.

An elongated lock bar 50 is slidable in the groove 10 of the body and has an end 52 which is complementary to and is adapted to abut the flange 14 of the pivot member.

40 The end of the bar 50 adjacent the lower end of the nut is transversely curving and inclined at 50' for engagement by the end lower portion 48' of the nut 48.

45 By screwing the nut 48 downwardly, the lower end thereof bears the end 50' of the lock bar 50 and urges the end 52 thereof against the flange of the pivot member to hold it against turning.

By loosening the nut 48, the pivot member may be turned to provide the desired angle of the blade and, thereafter, the nut may be tightened to bring about locking of the pivot member in the adjusted position.

45 The nut of the hook member may be loosened for longitudinal adjustment of the blade and subsequently tightened to maintain the adjustment.

The said nuts are readily accessible at the upper scale of the body so that the desired adjustments may be easily and readily accomplished.

50 The blade may take any form desired or such as will be found adaptable for various purposes and changes may be made in the form of the device without departing from the spirit and scope of the invention.

What I claim and desire to secure by Letters Patent of the United States is:

65 A bevel tool comprising in combination, an elongated straight-sided body provided with parallel upper and lower flat horizontal faces and having a pivot bore and a stud opening through forward and rear ends thereof with axes disposed transverse relative to the planes of said faces, the lower face of the body provided with a recess around said pivot bore, a pivot member rotatable in said

bore having an annular flange rotatably seated in said recess, an elongated bottom plate secured to the lower face of said body engaging and holding the flange of the pivot member in said recess and thereby the pivot member against axial displacement from said pivot bore, a threaded stud having a lower end fixed to said bottom plate and extending upwardly in the opening of the body, said body provided on the lower face thereof with a longitudinally extending groove extending between the pivot bore and stud opening thereof, a lock bar slidable in said groove having a forward end for bearing on the periphery of the flange of said pivot member to lock the same against rotation, the rear end of said lock bar provided with a bevel, a nut on said stud having a bevel for engaging said bevel of the lock bar to urge the said lock bar in forward locking direction, said pivot member provided with an axial opening and a slot in a side thereof disposed adjacent the upper face of the body and transverse to the

axis of said opening, an elongated blade reciprocable in said slot of the pivot member having a groove extending longitudinally thereof, a threaded hook member in said pivot member having a hook in the groove of the blade, and a nut disposed in the axial opening of the pivot member in threaded engagement with the hook member whereby to lock the blade against movement in said slot.
